Primary Examiner—Carol Rademaker(74) *Attorney, Agent, or Firm*—Brinks Hofer Gilson & Lione(57) **CLAIM**

I claim the ornamental design for a bottle, as shown and described.

DESCRIPTION

FIG. 1 is a side elevation view of a bottle showing the present invention, the front elevation view, rear elevation view, and opposite side elevation view being identical except for the unclaimed thread;

FIG. 2 is a bottom plan view thereof; and,

FIG. 3 is a top plan view thereof.

The broken lines shown in the drawings are for environmental purposes only and form no part of the claimed design.
